MACHINE FOR APPLYING PROTECTIVE COATINGS TO THE MARGINAL PORTIONS OF GRAMOPHONE DISCS

Thorwald Georg Gunnar Thoweman, Stockholm, Sweden

Application March 5, 1954, Serial No. 414,405

3 Claims. (Cl. 118—232)

This invention relates to a machine for treating 15 gramophone record discs and more particularly for applying a protective coating to the marginal portions of such discs.

The main object of the invention is to provide a machine capable of applying a protective coating to the 20 marginal portions of gramophone record discs, said coating serving as a spacer between adjacent discs when piled or placed in closed side to side relationship. The coating may, if colored, at the same time serve as indication for the type of recording carried by the disc.

Another object of the invention is to provide a machine of the kind defined which is capable of applying the said protective coating in a simple and inexpensive manner in connection with the finishing of the edge portion of the disc normally carried out by a grinding operation.

A still other object of the invention is to provide a machine capable of applying a smooth and thin protective coating to the marginal portions of the gramophone record disc, said coating being resilient and having a surface presenting a high friction against similar surfaces on adjacent discs in for instance record changer mechanism.

A further object of the invention is to provide gripping means for handling the gramophone record disc and securing it in the abovementioned machine during the finishing process and the following application of the marginal coating.

A machine embodying the invention is illustrated in the accompanying drawings, wherein:

Fig. 1 is a perspective view of the machine seen from behind,

Fig. 2 is a section of the rotatable support and the gramophone record disc secured thereto,

Fig. 3 is a partial front view of the support shown in Fig. 2,

Fig. 4 is a fragmentary view of the roller applying the coating to the marginal portions of the gramophone record disc,

Fig. 5 is an exploded cross-section of the support and gripping means for securing the gramophone record disc during treatment,

Fig. 6 is an exploded cross-section of a further modification of the disc attachment and handling means of Fig. 4,

Fig. 7 is a cross-section on the line 7—7 in Fig. 6 and

Fig. 8 is a frontal view of the support of Fig. 6, the seat member being removed.

Referring now to Figs. 1 to 4, the machine comprises a shaft 1 supported in bearings 2 and 3 carried by a bracket 4. Intermediate the bearings 2 and 3 a belt pulley 5 is secured to the shaft 1. A belt 6 from a motor (not shown) runs over the pulley 5 and imparts a continuous rotation to the shaft 1. The shaft 1 carries at one end a clamping disc 7 coupled to the shaft 1 for being driven thereby. Conveniently there may be pro-

2

vided a spring actuated coupling between the shaft 1 and the disc 7 normally keeping the disc 7 out of engagement with the shaft 1 but allowing firm connection therebetween when the disc 7 is pressed against the shaft end as will be explained later on. The clamping disc 7 is preferably covered with a soft coating of felt, rubber or the like and it has in its center a tapering bore 8 for a purpose to be explained in the following.

Turning now to the right end of Fig. 1, 9 designates 10 a second shaft coaxial to the shaft 1 and rotatably supported in spaced bearings 10 and 11 carried by a bracket 12. The shaft 9 is axially slidable in the bearings 10 and 11 and carries between said bearings a sleeve member 13, which is free on the shaft 9 and retained thereon by means of two annuli 14 and 15 rigidly fixed to the shaft 9 by screws 16 and 17 respectively. The lowermost portion of the sleeve member 13 has a downward projection 18 presenting a plane surface 19 sliding against a rail 20 extending parallelly to the shaft 9. This will prevent the sleeve member 13 from taking part in the rotation of the shaft 9.

The projection 18 or the sleeve member 13 has a shoe 21 to which a wire 22 is secured. This wire runs over a right hand pulley 23 supported for idling motion in a bracket 25 on the bracket 12 and a left hand pulley 24 similarly supported on the bracket 12. The left end portion of the wire 22 is connected to a spring loaded pedal 26 and the right end portion of the wire is similarly connected to a second spring loaded pedal 27. By depressing said pedals 26 and 27 alternatively the shaft 9 may, through the sleeve member 13 indisplaceably mounted thereon, be caused to move accordingly in either direction against the spring of the unactuated pedal. It should be noted that the said pedal springs 35 are calibrated to normally keep the shaft 9 in a neutral intermediate position when none of the pedals is actuated.

The end of the shaft 9 facing the clamping disc 7 on the shaft 1 carries a supporting disc 29 which is rigidly 40 connected to the shaft 9. On its back the supporting disc 29 has a tapering, frictional edge 31 which in the position of the supporting disc shown in Fig. 1, where the pedal 27 is assumed to be fully depressed, engages a tapering, frictional driving wheel 32, which is continuously driven by a second motor (not shown) to the shaft of which it is secured, to impart a relatively slow rotation to the supporting disc 29 in comparison to that of the coupled disc 7. Engagement between the driving wheel 32 and the supporting disc 29 only occurs 45 when the pedal 27 is depressed and thus when the pedal 27 is released no engagement will occur and the supporting disc will be at rest. Secured to the disc 29 there is a gramophone record disc 33 which is retained by means of a combined pick-up and connector tool 50 according to the invention and generally designated by 34 in Fig. 1.

Before referring to the particular design of the said tool 34 it may be mentioned that the machine shown in Fig. 1 is a combined finishing and coating machine.

60 When a gramophone record disc 33 is secured to the supporting disc 29 there is a considerable distance maintained between the supporting disc 29 and the clamping disc 7. As soon as the gramophone record disc 33 is in position the pedal 26 is depressed so that the disc 33 is clamped between the clamping disc 7 and the supporting disc 29 by the displacement of the latter with its shaft 9. The tool 34 is received within the bore 8 of the clamping disc 7 and the clamping disc 7 is pressed into engagement with the rotating shaft 1, so that the clamped gramophone record disc is set in rapid rotation. Now the disc 33 is ground by means of a manually operated grinding tool pressed against the periphery of the disc

33 in a conventional manner. When grinding is finished the pedal 26 is released and the pedal 27 depressed causing engagement between the supporting disc 29 and the driving wheel 32, so that the disc 33 will be retarded and continue to rotate at a low speed, say 50 R. P. M.

When the gramophone record disc 33 rotates at such lower speed a coating is applied to its marginal portions by means which will be described later on, and such coating will not set immediately. Therefore the gramophone record disc just treated cannot be grasped at its periphery and after all it is very unsatisfactory to handle the discs by the naked hand. Thus it will be quite necessary to have a particular tool for picking up and handling the record and particularly for removing it from the supporting disc 29. Such a tool should be able to safely grasp the record and permit securing thereof to the supporting disc 29 and it has been found that the most uncomplicated manner to obtain a suitable tool for such purpose is to make use of the central hole of the gramophone record disc.

One embodiment of such a tool is illustrated more particularly in Fig. 2, where the supporting disc 29 is provided with a central cavity 35 partially covered with a washer 36 fixed by means of screws to the front face of the supporting disc. Furthermore the disc 29 has threaded thereinto a central guide pin 38 having two opposed flats 39 and 40 as will be better seen from Fig. 3 which figure also shows that the washer 36 has two opposed notches 41 and 42 on either side of the guide pin. The tool 34 previously referred to comprises a flexible bow of steel having two shanks 43 and 44 each having a rigid lip extension 45 and 46 respectively sized to permit introduction thereof through the central hole of a gramophone record disc 33. Both lips 45 and 46 have a prong 47 and 48 respectively and the bow 34 has two support plates 49 and 50 having attached thereto resilient pads 51 and 52 respectively of sponge rubber or like material.

When grasping a record disc the bow shanks are pressed together so that the prongs 47 and 48 may pass through the central hole and then the bow is permitted to expand, so that the prongs will catch the disc 33 and pads 51 and 52 will stabilize it. Then the grasped disc 33 is lifted to the supporting disc 29 where the central pin 38 enters through the central hole of the disc 33 keeping the bow lips 45 and 46 spaced. By pressing the bow 34 towards the supporting disc 29 the prongs 47 and 48 are caused to enter through the notches 41 and 42 in the washer 36 and then the tool is slightly turned so that it will remain secured to the supporting disc 29 and retain the record disc 33 in proper position for treatment. When detaching the record from the support the tool is turned in opposite direction so that the prongs are extracted through the notches 41 and 42 by expansion of the pads 51 and 52 compressed during the attachment, and the record may easily be removed from the guide pin 38 and put aside. A slight pressure on the bow will release the tool 34 from the record disc.

Referring again to Fig. 1 the means for applying the protective coating to the marginal portions of the gramophone record disc 33 when the latter rotates at the lower speed in the machine as illustrated in Fig. 1 comprises a guide 53 for a sliding bracket 54. This bracket 54 comprises two protruding arms 55 and 56 having forked ends 57 carrying a dispenser wheel generally designated by 59, which is free to rotate and carried by a shaft 60. Between the arms 55 and 56 of the sliding bracket 54 there is a second, forked bracket 61 which may be adjusted relatively to the bracket 54 by means of a screw 55 threaded into the latter. The outer ends 62 of the bracket 61 carries a shaft 64 for a freely rotatable stripping roller 65 adapted to be pressed against the dispenser wheel 59 with a desired force. A suitable splash-tray 66 is located on the sliding bracket 54 below the stripping roller 65.

Attached to the rear end of the guide 53 is a spring pulley 67 over which is coiled a wire 68, the end of which

is secured to the sliding bracket 54, so that the latter will be tensioned away from the record disc 33. Extending from the bracket 54 there is further a rod 69 terminating in a handle 70, by means of which the dispenser wheel 59 may be temporarily pressed into engagement with the edge of the rotating record disc. The dispenser wheel 59 which is also shown in Fig. 4 comprises a hollow body serving as a container for the liquid coating substance to be applied to the record disc. The coating substance is introduced in said hollow body through a lateral aperture therein closed by a cap or the like (not shown). Around the periphery or envelope surface 72 of the hollow body the diameter is slightly reduced and there are provided perforations 73 leading into the hollow body. The perforated envelope surface is covered by a permeable, cushiony annular pad 74 which in turn is wrapped by an annular permeable and flexible screen, preferably having a mesh width 15—13 darning and manufactured of synthetic filaments:

20 By pulling the handle 70 the dispenser wheel 59 may temporarily be brought into contact with the rotating record disc 33 and pressed thereagainst so that the disc edge forms a groove in the screen and the pad 74 thereby obtaining a coating both on the edge proper and its 25 marginal flat surfaces to some degree. The screen serves to distribute the coating substance to form a smooth coating of a very minor thickness on the edge and marginal portions of the record disc. Though the coating is very thin it has proved satisfactory to meet the demands 30 for an inexpensive but reliable protection for the record discs when piled, stored, handled or used in record changer mechanism. The dispenser wheel 59 only has to be pressed against the record disc during one or a few revolutions of the latter. After having been so coated the record 35 disc should be placed away so that the coating is allowed to set:

The combined tool according to the invention may 40 obviously be modified in several respects and to show this two further embodiments thereof will be described with reference to Fig. 5 and Figs. 6 to 8 inclusive.

In Fig. 5 the modified tool comprises a foot 71 having its bottom covered with a layer 72 of soft and resilient material such as sponge rubber. To the foot is threaded a sleeve 73 carrying a slideable knob 74 and enclosing a 45 pipe 75 having a point 76 pressed into its frontal mouth protruding through the foot 71. The pipe has an external flange 77 intermediate its ends between which and the foot 71 there is provided a helical spring 78. Between the flange 77 and a free washer 79 surrounding the pipe 75 there is a weaker spring 80. Slidably arranged within the pipe 75 is a rod 83 having a cross pin 81 behind the washer 79 and passing through longitudinal slots 90 and 91 in the pipe 75. The knob 74 is closed by a threaded washer 82 secured to the slotted end of the pipe 75. The rod 83 terminates in a releasing button 84. The opposite end of the rod 83 has a longitudinal slot 85 for receiving the inner ends of two jointed jaw members 86 and 87 having each a frontal detent 88 and 89 respectively protruding through each one slot in the pipe 75 behind the point 76 in a resilient manner.

When grasping a fresh record disc the point 76 is simply pressed through the central hole of the disc 33 and the detents 88, 89 will readily snap out outside the disc for retaining it on the tool. When securing the record disc 65 33 and the tool to the supporting disc 29 of the machine hereinbefore described the latter must be provided with a central hole having a lining 93 preferably threaded thereto. It has been found advantageous to provide a funnel-like recess 92 around this lining 93, which will facilitate positioning. The point 76 and the outer end of the pipe 75 is simply pushed into the lining 93 by pressing the knob 74 so that the detents 88 and 89 will snap in behind the lining 93.

When releasing the disc 33 and the tool from support 75 ing disc 29 the button 84 is pushed whereby the detents

88 and 89 are drawn into the pipe 75 by the forked end of the rod 83. The spring 78 will extract the point 76 out of the lining 93 and the button 84 is rapidly released so that the detents 88 and 89 will again catch the record disc 33 while the point 76 still centers in the lining 93. Then the tool with the record disc is removed from the supporting disc 29 and the record disc 33 may be dropped in suitable place by again pushing the button 84.

With reference to Figs. 6 to 8 numeral 94 designates a turned handle having a cover 95 of relatively slippery cloth or the like on its disc facing surface. In the top of the tool there is a push button 96 into which is screwed one end of a rod 98 having a square or unround cross-section. Around the rod 98 there is provided a spring 97 between the handle 94 and the button 96. The rod 98 is slidable but not turnable in the handle 94 and has an enlarged point 101 projecting from the disc facing surface of the handle. Between the inner side of this point or head 101 and a bushing 100 fixed to the rod 98 by means of a pin 99 is anchored the outer end of a rubber mantle 104, the rear end of which is secured to the handle 94 by a wire ring 106 and a threaded washer 105. The point 101 as better seen in Fig. 7 is provided with two opposite and parallel and transverse slots 102 and 103.

When using the tool of Fig. 6 the supporting disc should, as apparent from the left part of Fig. 6, have a central recess 112 for receiving the point 101 of the tool. Around the recess 112 there is provided a square block 109 having a central hole inside of which there are provided two leaf springs 107 and 108 kept in place by two projections 110 and 111. In picking up the record disc 33 by means of the recently described tool the button 96 of the tool is pushed so that the rubber mantle 104 is extended when the point 101 is passed through the central hole of the record disc 33. Then the button 96 is released causing the rubber mantle 104 to form an angular bulge outside the disc 33 as shown. Securing of the disc 33 and the tool to the support 29 is attained by simply entering the point 101 into the recess 112 and turning the tool so that the leaf springs 107 and 108 will snap into the respective slots 102 and 103. Releasing of the tool from the support is again obtained by turning the tool in either direction a quarter of a revolution whereby the leaf springs will release the point 101 for extraction. The record disc is dropped away by again pressing the button 96. It should be mentioned that in this latter case it is important that the support 29 has a covering 113 which is soft and frictionally engages the record disc to prevent it from freely rotating on the support.

The invention is not limited of course to the embodiment and details herein shown and described but may be varied in several respects within the scope of the appended claims.

I claim:

1. In a machine for treating gramophone record discs; the combination of an annular support plate adapted to receive a record disc in closely abutting relation to one of the radial faces of said plate, means for retaining a record disc against said one face of the support plate, a shaft rigidly connected to said plate and extending axially from the other face of the latter, bearing means having said shaft journaled therein for rotational and axial movement of the shaft, means for selectively displacing said shaft in the axial direction for moving said support plate between first and second axially spaced apart positions, drive means engageable with said support plate only at said first position of the latter to there rotate the support plate at a relatively slow rotational speed, a rotary dispensing roller adjacent said first position of the support plate and movable toward and away from the latter in the radial plane of the support plate for applying a protective coating to a record disc held against said support plate at said first position, means for displacing said dispensing roller in said radial plane to engage and release the edge of a record disc, an annular drive plate rotatably mounted

adjacent said second position of the support plate coaxially with the latter to frictionally engage a record disc held against said support plate when the latter is moved to said second position, and means rotating said drive plate at a relatively high rotational speed so that a record disc held against said support plate and frictionally engaged by said drive plate will be rotated by the latter at a speed suitable for the grinding of the edge and marginal portions of the record disc.

- 5 2. In a machine for treating gramophone record discs; the combination of a rotatable support, means for securing a gramophone record disc to said support concentrically with the axis of rotation thereof, means for imparting rotary motion to said support and hence to the gramophone record disc secured thereto, and means for applying a coating to the marginal and edge surfaces of the gramophone record disc, said coating means including a rotatable dispenser roller having its axis of rotation parallel to the axis of the secured gramophone record disc and being displaceable in the radial plane of the latter and actuator means for temporarily pressing said roller into engagement with the marginal portions of the gramophone record disc, and roller comprising a hollow body having a perforated envelope surface, and a permeable, flexible member surrounding said perforated envelope surface of said hollow body and capable of being circumferentially indented by contact with the edge of the record disc, said hollow body being adapted to contain a liquid coating substance capable of penetrating said permeable, flexible member, and said means for securing the gramophone record disc to said support comprising a gripping handle including members adapted to enter the central hole of the gramophone record disc, expandable means for hooking the gramophone record disc to said handle and means for securing the handle to said support so that, following the application of a liquid coating substance to the edge and marginal portions of the record disc, the latter can be removed from said support without requiring handling of the disc.
- 10 3. In a machine for treating gramophone record discs; the combination of a rotatable support movable axially between two operative positions, means for securing a gramophone record disc said support concentrically with the axis of rotation thereof, means disposed adjacent one 15 of said operative positions of said support for applying a coating to the marginal and edge surfaces of a gramophone record disc secured to said support as the latter is rotated at said one operative position thereof, said coating means including a rotatable dispenser roller having its axis of rotation parallel to the axis of the secured gramophone record disc and being displaceable in the radial plane of the latter at said one operative position of the support and actuator means for temporarily pressing said roller into engagement with the marginal portions of the gramophone record disc, said roller comprising a hollow body having a perforated envelope surface and a permeable, flexible member surrounding said perforated envelope surface of said hollow body and capable of being circumferentially indented by contact with the edge of the record disc, said hollow body being adapted to contain a liquid coating substance capable of penetrating said permeable, flexible member, means for imparting rotary motion to said support including a first rotary drive means operative to impart a relatively slow rotation to said support suitable for the application of a liquid coating to the edge and marginal portions of a record disc secured on said support when it is located axially at said one position and a second rotary drive means operative to impart a relatively rapid rotation to said support when the latter is disposed at the other of said operative positions thereof so that the edge and marginal portions of a record disc on said support may be ground with the latter in said other position, and means normally retaining said support axially intermediate said two positions, so that the support is rotationally at rest
- 20 4. In a machine for treating gramophone record discs; the combination of a rotatable support, means for securing a gramophone record disc to said support concentrically with the axis of rotation thereof, means for imparting rotary motion to said support and hence to the gramophone record disc secured thereto, and means for applying a coating to the marginal and edge surfaces of the gramophone record disc, said coating means including a rotatable dispenser roller having its axis of rotation parallel to the axis of the secured gramophone record disc and being displaceable in the radial plane of the latter and actuator means for temporarily pressing said roller into engagement with the marginal portions of the gramophone record disc, and roller comprising a hollow body having a perforated envelope surface, and a permeable, flexible member surrounding said perforated envelope surface of said hollow body and capable of being circumferentially indented by contact with the edge of the record disc, said hollow body being adapted to contain a liquid coating substance capable of penetrating said permeable, flexible member, and said means for securing the gramophone record disc to said support comprising a gripping handle including members adapted to enter the central hole of the gramophone record disc, expandable means for hooking the gramophone record disc to said handle and means for securing the handle to said support so that, following the application of a liquid coating substance to the edge and marginal portions of the record disc, the latter can be removed from said support without requiring handling of the disc.
- 25 5. In a machine for treating gramophone record discs; the combination of a rotatable support movable axially between two operative positions, means for securing a gramophone record disc said support concentrically with the axis of rotation thereof, means disposed adjacent one 30 of said operative positions of said support for applying a coating to the marginal and edge surfaces of a gramophone record disc secured to said support as the latter is rotated at said one operative position thereof, said coating means including a rotatable dispenser roller having its axis of rotation parallel to the axis of the secured gramophone record disc and being displaceable in the radial plane of the latter at said one operative position of the support and actuator means for temporarily pressing said roller into engagement with the marginal portions of the gramophone record disc, said roller comprising a hollow body having a perforated envelope surface and a permeable, flexible member surrounding said perforated envelope surface of said hollow body and capable of being circumferentially indented by contact with the edge of the record disc, said hollow body being adapted to contain a liquid coating substance capable of penetrating said permeable, flexible member, means for imparting rotary motion to said support including a first rotary drive means operative to impart a relatively slow rotation to said support suitable for the application of a liquid coating to the edge and marginal portions of a record disc secured on said support when it is located axially at said one position and a second rotary drive means operative to impart a relatively rapid rotation to said support when the latter is disposed at the other of said operative positions thereof so that the edge and marginal portions of a record disc on said support may be ground with the latter in said other position, and means normally retaining said support axially intermediate said two positions, so that the support is rotationally at rest
- 35 6. In a machine for treating gramophone record discs; the combination of a rotatable support, means for securing a gramophone record disc to said support concentrically with the axis of rotation thereof, means for imparting rotary motion to said support and hence to the gramophone record disc secured thereto, and means for applying a coating to the marginal and edge surfaces of the gramophone record disc, said coating means including a rotatable dispenser roller having its axis of rotation parallel to the axis of the secured gramophone record disc and being displaceable in the radial plane of the latter and actuator means for temporarily pressing said roller into engagement with the marginal portions of the gramophone record disc, and roller comprising a hollow body having a perforated envelope surface, and a permeable, flexible member surrounding said perforated envelope surface of said hollow body and capable of being circumferentially indented by contact with the edge of the record disc, said hollow body being adapted to contain a liquid coating substance capable of penetrating said permeable, flexible member, and said means for securing the gramophone record disc to said support comprising a gripping handle including members adapted to enter the central hole of the gramophone record disc, expandable means for hooking the gramophone record disc to said handle and means for securing the handle to said support so that, following the application of a liquid coating substance to the edge and marginal portions of the record disc, the latter can be removed from said support without requiring handling of the disc.
- 40 7. In a machine for treating gramophone record discs; the combination of a rotatable support movable axially between two operative positions, means for securing a gramophone record disc said support concentrically with the axis of rotation thereof, means disposed adjacent one 45 of said operative positions of said support for applying a coating to the marginal and edge surfaces of a gramophone record disc secured to said support as the latter is rotated at said one operative position thereof, said coating means including a rotatable dispenser roller having its axis of rotation parallel to the axis of the secured gramophone record disc and being displaceable in the radial plane of the latter at said one operative position of the support and actuator means for temporarily pressing said roller into engagement with the marginal portions of the gramophone record disc, said roller comprising a hollow body having a perforated envelope surface and a permeable, flexible member surrounding said perforated envelope surface of said hollow body and capable of being circumferentially indented by contact with the edge of the record disc, said hollow body being adapted to contain a liquid coating substance capable of penetrating said permeable, flexible member, means for imparting rotary motion to said support including a first rotary drive means operative to impart a relatively slow rotation to said support suitable for the application of a liquid coating to the edge and marginal portions of a record disc secured on said support when it is located axially at said one position and a second rotary drive means operative to impart a relatively rapid rotation to said support when the latter is disposed at the other of said operative positions thereof so that the edge and marginal portions of a record disc on said support may be ground with the latter in said other position, and means normally retaining said support axially intermediate said two positions, so that the support is rotationally at rest
- 50 8. In a machine for treating gramophone record discs; the combination of a rotatable support, means for securing a gramophone record disc to said support concentrically with the axis of rotation thereof, means for imparting rotary motion to said support and hence to the gramophone record disc secured thereto, and means for applying a coating to the marginal and edge surfaces of the gramophone record disc, said coating means including a rotatable dispenser roller having its axis of rotation parallel to the axis of the secured gramophone record disc and being displaceable in the radial plane of the latter and actuator means for temporarily pressing said roller into engagement with the marginal portions of the gramophone record disc, and roller comprising a hollow body having a perforated envelope surface, and a permeable, flexible member surrounding said perforated envelope surface of said hollow body and capable of being circumferentially indented by contact with the edge of the record disc, said hollow body being adapted to contain a liquid coating substance capable of penetrating said permeable, flexible member, and said means for securing the gramophone record disc to said support comprising a gripping handle including members adapted to enter the central hole of the gramophone record disc, expandable means for hooking the gramophone record disc to said handle and means for securing the handle to said support so that, following the application of a liquid coating substance to the edge and marginal portions of the record disc, the latter can be removed from said support without requiring handling of the disc.
- 55 9. In a machine for treating gramophone record discs; the combination of a rotatable support, means for securing a gramophone record disc to said support concentrically with the axis of rotation thereof, means for imparting rotary motion to said support and hence to the gramophone record disc secured thereto, and means for applying a coating to the marginal and edge surfaces of the gramophone record disc, said coating means including a rotatable dispenser roller having its axis of rotation parallel to the axis of the secured gramophone record disc and being displaceable in the radial plane of the latter and actuator means for temporarily pressing said roller into engagement with the marginal portions of the gramophone record disc, and roller comprising a hollow body having a perforated envelope surface, and a permeable, flexible member surrounding said perforated envelope surface of said hollow body and capable of being circumferentially indented by contact with the edge of the record disc, said hollow body being adapted to contain a liquid coating substance capable of penetrating said permeable, flexible member, means for imparting rotary motion to said support including a first rotary drive means operative to impart a relatively slow rotation to said support suitable for the application of a liquid coating to the edge and marginal portions of a record disc secured on said support when it is located axially at said one position and a second rotary drive means operative to impart a relatively rapid rotation to said support when the latter is disposed at the other of said operative positions thereof so that the edge and marginal portions of a record disc on said support may be ground with the latter in said other position, and means normally retaining said support axially intermediate said two positions, so that the support is rotationally at rest
- 60 10. In a machine for treating gramophone record discs; the combination of a rotatable support, means for securing a gramophone record disc to said support concentrically with the axis of rotation thereof, means for imparting rotary motion to said support and hence to the gramophone record disc secured thereto, and means for applying a coating to the marginal and edge surfaces of the gramophone record disc, said coating means including a rotatable dispenser roller having its axis of rotation parallel to the axis of the secured gramophone record disc and being displaceable in the radial plane of the latter and actuator means for temporarily pressing said roller into engagement with the marginal portions of the gramophone record disc, and roller comprising a hollow body having a perforated envelope surface, and a permeable, flexible member surrounding said perforated envelope surface of said hollow body and capable of being circumferentially indented by contact with the edge of the record disc, said hollow body being adapted to contain a liquid coating substance capable of penetrating said permeable, flexible member, and said means for securing the gramophone record disc to said support comprising a gripping handle including members adapted to enter the central hole of the gramophone record disc, expandable means for hooking the gramophone record disc to said handle and means for securing the handle to said support so that, following the application of a liquid coating substance to the edge and marginal portions of the record disc, the latter can be removed from said support without requiring handling of the disc.
- 65 11. In a machine for treating gramophone record discs; the combination of a rotatable support, means for securing a gramophone record disc to said support concentrically with the axis of rotation thereof, means for imparting rotary motion to said support and hence to the gramophone record disc secured thereto, and means for applying a coating to the marginal and edge surfaces of the gramophone record disc, said coating means including a rotatable dispenser roller having its axis of rotation parallel to the axis of the secured gramophone record disc and being displaceable in the radial plane of the latter and actuator means for temporarily pressing said roller into engagement with the marginal portions of the gramophone record disc, and roller comprising a hollow body having a perforated envelope surface, and a permeable, flexible member surrounding said perforated envelope surface of said hollow body and capable of being circumferentially indented by contact with the edge of the record disc, said hollow body being adapted to contain a liquid coating substance capable of penetrating said permeable, flexible member, means for imparting rotary motion to said support including a first rotary drive means operative to impart a relatively slow rotation to said support suitable for the application of a liquid coating to the edge and marginal portions of a record disc secured on said support when it is located axially at said one position and a second rotary drive means operative to impart a relatively rapid rotation to said support when the latter is disposed at the other of said operative positions thereof so that the edge and marginal portions of a record disc on said support may be ground with the latter in said other position, and means normally retaining said support axially intermediate said two positions, so that the support is rotationally at rest
- 70 12. In a machine for treating gramophone record discs; the combination of a rotatable support, means for securing a gramophone record disc to said support concentrically with the axis of rotation thereof, means for imparting rotary motion to said support and hence to the gramophone record disc secured thereto, and means for applying a coating to the marginal and edge surfaces of the gramophone record disc, said coating means including a rotatable dispenser roller having its axis of rotation parallel to the axis of the secured gramophone record disc and being displaceable in the radial plane of the latter and actuator means for temporarily pressing said roller into engagement with the marginal portions of the gramophone record disc, and roller comprising a hollow body having a perforated envelope surface, and a permeable, flexible member surrounding said perforated envelope surface of said hollow body and capable of being circumferentially indented by contact with the edge of the record disc, said hollow body being adapted to contain a liquid coating substance capable of penetrating said permeable, flexible member, and said means for securing the gramophone record disc to said support comprising a gripping handle including members adapted to enter the central hole of the gramophone record disc, expandable means for hooking the gramophone record disc to said handle and means for securing the handle to said support so that, following the application of a liquid coating substance to the edge and marginal portions of the record disc, the latter can be removed from said support without requiring handling of the disc.
- 75

for permitting the mounting of a record disc on, and the removal of a record disc from, said support, and being operative to selectively displace said support to each of said two operative positions.
